CLAIM

The ornamental design for a storage case insert, as shown and described.

DESCRIPTION

This application is related to a Design patent application Ser. No. 29/346,143 entitled "Storage Case", a Design patent application Ser. No. 29/346,142 entitled "Ear Bud", and a Utility patent application Ser. No. 12/606,879 entitled "Aural Device with White Noise Generator", all filed on even date herewith.

FIG. 1 is a perspective view of a storage case insert according to the present invention;

FIG. 2 is a top plan view of the storage case insert of FIG. 1;

FIG. 3 is a bottom plan view of storage case insert of FIG. 1; FIG. 4 is a side elevation view of the storage case insert of FIG. 1 taken from the right side of FIG. 2;

FIG. 5 is a side elevation view of the storage case insert of FIG. 1 taken from the left side of FIG. 2;

FIG. 6 is a front elevation view of the storage case insert of FIG. 1; and,

FIG. 7 is a rear elevation view of the storage case insert of FIG. 1.
